UNITED STATES PATENT OFFICE.

VICTOR E. BEAGLE, OF BINGHAMTON, NEW YORK.

HOISTING-TRUCK.

1,186,876.

Specification of Letters Patent. Patented June 13, 1916.

Application filed May 15, 1915. Serial No. 28,370.

To all whom it may concern:

Be it known that I, VICTOR E. BEAGLE, a citizen of the United States, residing at Binghamton, in the county of Broome and State of New York, have invented certain new and useful Improvements in Hoisting-Trucks, of which the following is a specification.

The invention has for an important object 10 to provide a truck adjustable to embrace articles of various sizes and shapes, with hoisting means engageable with such objects as the truck may be adjusted to.

It is an important object to improve the 15 manner of lifting heavy objects upon small trucks or large trucks, the device being readily applicable to use for handling both large and small articles.

A further aim is to give an improved construction in the framing of a truck.

Another purpose is to provide means to enable the adjustment of lifting elements on a truck to engage an article in the most advantageous way, with respect to positioning 25 the lifting elements relatively to the center of specific gravity of the object to be lifted, or to engage the objects at points least liable to damage by reason of its weight, abrasion, or otherwise.

Additional objects, advantages and features of invention will be apparent from the construction, arrangement and combination of parts herein after described and shown in the drawings, where,

Figure 1 is a plan view of a truck constructed in accordance with my invention, Fig. 2 is a side elevation thereof, Fig. 3 is a cross section of one of the sides of frame showing the construction of one of the jacks, 40 and its mounting on the frame, Fig. 4 is an inner side elevation of one of the jack elements, Fig. 5 is a detail of the tongue element of the truck, Fig. 6 is a side elevation of a modification, Fig. 7 is a fragmentary plan view of a further modified construction of the frame, wherein the pivotal connections between the frame element are obviated, Fig. 8 is a detail elevation of one 45 form of jack especially desirable for use with this invention, Fig. 9 is a detail of the mounting and adjusting means for the

last named jack, Fig. 10 is a cross sectional view of a truck frame equipped with jacks of the last mentioned type, illustrating one manner of use thereof, Fig. 11 is a detail 55 of the mounting for such a jack upon an I beam.

There is illustrated a truck comprising in Figs. 1 to 6 a frame including a transverse head piece 11, centrally of which there is 60 fixed a wear plate 12, upon which is pivoted the yoke 13 having the enlarged head portion 14 of circular form seated snugly against the plate, a wheel 15 being revolvably mounted between the arms of the yoke, and 65 a suitable steering fork 16 being also pivotally connected with the yoke as shown, including the hollow shank portion 17. Pivoted at each end of the cross piece 11, there are short links 18, to the outer ends 70 of which there are pivotally connected respective side pieces 19, shown as formed of channel iron, and comprising the sides proper of the frame 10. Fixed upon the rear end portion of these side members 19 75 there are casters 20, of any suitable construction, and if desired an additional caster may be mounted at the forward part of these side members.

The plate 12 is extended rearwardly 80 within the frame and provided with a downward extension 21, formed with a suitable channel on its inner side receiving slidably a jack foot piece 22, for vertical sliding movement, this foot piece being provided 85 with a vertical worm shank 23, engaged in a suitable nut 24 engaged upon the upper part of the extension formed with a beveled gear face with which there is meshed a corresponding gear 25 revolvably mounted on 90 the side of an upward extension 26 from the plate 12. Commonly pivoted on the axis of the gear 25 there is a lever 27, having a reversible pawl 28 thereon, arranged to engage peripheral teeth on the gear 25 under 95 movement of the lever in one direction, whereby the jack device may be operated by oscillation of the lever. The parts 21 to 28 inclusive are substantially duplicated in the parts 31 *et seq.*, shown in large detail in 100 Figs. 3 and 4.

Engaged slidably on the side members 19

there are jack bases 30, comprising an inner vertical portion 31 having a suitable channel formed on the inner side, this vertical portion extending below the frame, and the channel opening through its bottom end. The vertical portion is formed with a short upward extension 32 directly over the channel 31, to receive the worm shank 33 of a jack foot 34 vertically movable in the channel 31. A gear nut 35 is engaged on the worm and held against upward movement by a suitable caging 36 therearound and formed integrally on the extension 32, a stub shaft 37 being formed on the side of the extension 32 upon which there is revolvably mounted a gear 38 meshed with the gear 35, a lever 39 being pivoted on the outer part of the shaft provided with a pawl 40 arranged to engage peripheral teeth on the gear 38 for its operation, in the manner well understood in such jacks. The jack base is formed with integral outwardly extended portions 41, arranged to embrace the channel irons of the side members snugly, having inturned portions 42 engaging around the edges of the channel iron whereby the jack bases are held snugly upon the side members for sliding movement. If desired a set screw or other means may be provided as at 43 to hold the jack bases against sliding movement on the side members of the frame 10. The number of jack elements on the side members of the frame may be increased to any extent found desirable. The rear ends 35 of the side members are adjustably connected together by means of a chain 54 or other connecting member, the chain being releasable at one side at least, and any suitable means provided whereby the chain may 40 be let out to connect the side members at various distances apart.

In the hollow shank 17 of the front steering forks 16, a bar 44 is inserted, having its inner end shaped like that of the usual "pinch bar", and being releasably secured in the shank 17 by means of a pin 45 removably inserted through suitable apertures in the shank and the bar.

Various forms of jack constructions may 50 be employed other than that described, and I do not regard the invention as limited to the exact structure of any of the parts set forth. Thus, it may be found desirable to construct the side members of the frame as 55 indicated in Fig. 7, where the front wheel and the yoke 13 by which it is carried are mounted on a body structure 46, having a transverse passage therethrough and provided with a clamping bolt 47 arranged to 60 be projected into the passage, from above. The side elements 47 each comprise right angular pieces of suitable material having a short forward arm 47 engaged slidably through the passage in the member 46, the 65 parts 47 of opposite side pieces being ar-

ranged in overlapped superposed position, and secured by the bolt 43 against lateral movement. I also include a much longer side arm 48 fixed with relation to the arm 47, and if desired formed integrally therewith, upon which suitable jacks and supporting wheels may be mounted as before described in connection with the showing in Fig. 1.

It may be desired to secure the side pieces of the frame in fixed parallel relation, so that the device may be used as an ordinary truck of fixed sides, and in this event, it may be found desirable to secure the caster members at the rear end against swivel movement, for which purpose a pin 50 may be provided to be engaged through the pivot framing of the caster and with the wear plates at the head of the forks, as shown.

The device as before stated is adaptable to construction in various sizes, and may be formed if desired with other styles of wheels than casters, this being suggested in Fig. 6, where the frame is elevated at the forward part and mounted in any customary manner upon a two wheeled truck such as is customarily used in heavy wagon construction, and each side member is provided with a heavy wheel 52 at its rear part. The intermediate link 18 between the forward piece of the frame and the side pieces may be eliminated in the heavier trucks, if desired.

Any suitable extensible means may be used between the rear ends of the side members of the frame to form extensible connections, and one method is suggested, which consists in securing a chain to the rear end of one side, as at 54 in Fig. 1, extending the chain then to the end of the opposite side member and then forwardly within the channel iron on the outer side, a hook being provided at the free end of the chain and suitable openings formed in the channel iron with which the hook may be engaged at a suitable point to limit the width of the frame at the rear part.

In use, when an object is to be moved the frame of the truck is opened up sufficiently to receive the object in its rear open end, which is then presented toward the object and the truck backed into place with the side members on each side of the object and the foot piece 22 of the forward jack engaging beneath the object. The engagement of this foot piece may be greatly facilitated by withdrawing the pinch bar handle from the hollow shank 17 of the steering fork and raising the object therewith sufficiently to enable the foot piece 22 to pass thereunder. The forward jack is then operated to raise the object to a distance which will permit the foot pieces of the jack on the side members to engage thereunder, when the side members are moved inwardly

for this purpose and the foot pieces of the respective jacks engaged under the object at each side. The rear ends of the side members are then connected to prevent their separation, and the rear jacks operated. It may then be readily moved by securing the pinch bar in the steering forks. Substantially the same method may be pursued with any sizes of the truck when any object is to be raised. The truck is designed for use in moving general freight, pianos, heavy stone blocks, machinery, structural iron, and various other heavy or light materials.

It will be apparent that the truck is extremely simple and inexpensive in construction, and that it may be readily manipulated without difficulty. It will obviate the necessity for moving of extremely heavy objects such as stone, machinery, and the like in order to get them into position upon a truck for removal, it being possible to adjust the truck itself in position around the object instead of requiring the object to be moved to the truck, and the initial jacking up of the object is sufficient to raise it into proper position upon the truck for removal, instead of requiring the operations which have heretofore intervened, of moving the object laterally on to the truck, ordinarily involving extremely laborious work, and a considerable expenditure of time.

There is illustrated in Figs. 8, 9, and 10 an improved mounting of the jacks which it may be found desirable to use, and which consists in providing a base element 55, which may be either slidable on the channel iron of the frame as shown at 57, or fixed thereon as shown at 56. This base is formed with arms 58 extending upwardly and carrying a transverse shaft 59, upon which there is pivoted a heavy ear 60 formed at the back of a jack base 30', which may otherwise be constructed and equipped in the same way that the jack elements already described were. By this arrangement it can be seen that the jacks are adapted to be so inclined that they may engage objects having a considerable overhang, and they may be operated for hoisting in the same manner as the first described jacks, their inclination having no tendency to interfere with manipulation of the operating lever. In order to enable the jacks to be held in various inclined positions, a rack-toothed lever 61 is pivoted between suitable ears 62 on the back of the jack base 30', the lever being curved and provided with a finger-hold 63 at its outer end by which it may be lifted. The teeth are engageable with a tooth or lip 64 formed on the base 55 and projected upwardly in suitable form for engagement with the teeth of the lever. The lever 61 is pivoted on the jack base a distance below the ear 60, so that the lower part of the jack 65 will be supported in various positions by the

lever. The lever will fall by gravity into engagement with the tooth 64. In these views the foot 34' of the jack is provided with a pin or trunnion 65, so that a chain 66 may be engaged upon the pins of two opposed similar jacks, as shown in Fig. 10, enabling a pipe or other object with a great overhang at the sides to be transported.

What is claimed:

1. A truck of the class described comprising a frame having a forward wheeled element side members pivoted thereon and adjustable laterally the frame being constructed for disposition in embracing relation to an object to be transported, and means carried by the truck frame at the inner side for engagement with objects to be transported.

2. A truck of the class described comprising in a frame including a forward wheeled element, side members connected thereto for lateral movement to adjust the frame to the width of various objects to be transported, wheels carried by the side members, means carried at the inner side of the frame for engagement with an object to be transported, and means at the rear end of the side members for securing them against divergent movement.

3. A truck of the class described comprising a frame including a forward wheeled element, laterally adjustable side members connected to the forward end thereof, wheels to support the side members, the frame being open at its rear part and a plurality of jack members located fore and aft having inwardly projecting toe pieces to engage under objects to be transported.

4. A truck element for uses described, comprising a wheeled frame including a front member, link elements connected to respective sides thereof, and side members pivotally connected to the outer ends of said links, respective wheels carried by the side elements and lifting devices carried by the forward member and side members respectively, for the purposes described.

5. A truck of the class described comprising a wheeled frame including a forward member and side members connected thereto, the frame being open at its rear part and hoisting jack members carried by the forward member and side members of the frame respectively, said jack members on the side members being longitudinally slidable thereon.

6. In a device of the class described, a frame having opposed jack bases pivoted thereon, having portions extended below and above the pivots and a lifting member slidably therein having a foot piece extending laterally from the inner side for the purposes described and means to operate the lifting member.

7. In a device of the class described, a

frame, a jack base having a slidable lifting element therein and pivoted on the frame for extension of the lifting member inwardly at one part at times, means to operate the lifting member, and means to support the base in various inclined positions.

In testimony whereof I have affixed my signature in presence of two witnesses.

VICTOR E. BEAGLE.
